Gertrude G. Condon
BY *M. C. Frank*
ATTORNEY

UNITED STATES PATENT OFFICE.

GERTRUDE G. CONDON, OF OAKLAND, CALIFORNIA.

HAIR CURLER.

Application filed February 16, 1924. Serial No. 693,262.

To all whom it may concern:

Be it known that I, GERTRUDE G. CONDON, a citizen of the United States, residing at Oakland, in the county of Alameda and 5 State of California, have invented certain new and useful Improvements in Hair Curlers, of which the following is a specification.

The present invention relates to hair 10 curlers, and has for its principal object to overcome certain faults that invariably exist in every similar type of hair curler heretofore devised that I am aware of. Briefly, the chief faults are that they will not curl 15 the extreme end of the hair, and will not marcel and curl in the same operation.

Other important objects of the invention are; that the curler is adapted to engage the very tip ends of the hair, whether it is a 20 small amount or a large amount and hold the same securely; that the curler is adapted to form a tight as well as a loose curl; that the hair may be curled and marcelled in one operation; that the holding means is 25 positive and compact; that the curler can be removed from the hair without unwinding by simply disengaging the holding means and slipping the jaws thereof out of the hair laterally; that the curler will 30 grip and curl the short hairs on the back of the head at the neck, thus making it possible to curl the heretofore straight fringe of hair thereat, as the use of a hot curling iron contacts the skin with painful effects.

35 Other advantages and improvements in the present device will readily appear from the following description of the accompanying sheet of drawings.

In said drawings: Figure 1 is a perspective view of the device unlocked; Fig. 2 is a similar view but showing the device locked; Fig. 3 is a view in perspective, showing the manner of handling the curler when about to use the same; Fig. 4 is a similar 45 view showing the hair engaged as the first step in applying the device; Fig. 5 is a view of the device with the hair engaged therein, to produce a curl on the ends of the hair, and Fig. 6 is a side view of the produced curl, showing to advantage the tight curl at the end thereof; Fig. 7 is a view of the hair engaged by the curler in a manner to produce a so called Marcel wave; Fig. 8 is a cross-section on the line 8—8 of Fig. 7, 50 showing the tip ends of the hair engaged between the jaws and the balance of the

hair engaged thereabout; and Fig. 9 is a view showing the combined Marcel wave and end curl produced by the engagement shown in Fig. 7.

Referring to the drawings in detail: the letter A represents the frame member of the device which I prefer to make from wire, although it may be punched from sheet metal, and is so formed as to provide side bars represented by the numerals 6 and 7, and end bars by 8 and 9. The side bars are of a suitable length and extend parallel to one another and merge into the end bars. The latter bars may be so bent or otherwise 70 formed, as to leave shoulders 10 at the four corners of the frame.

These shoulders or their equivalent are important, since they provide an abutment or stop for the sliding lock ring 11 of the 75 device. This ring 11 is made to straddle and slide freely on the side bars for the entire length thereof.

Sharply looped around or otherwise pivoted to the end bar 9 is a pair of jaws 12, 80 adapted to be freely moved in a vertical plane between the side bars 6 and 7. The jaws normally diverge somewhat, so that when free of the locking ring 11, they will spring apart for a portion of their length. The jaws for this purpose are preferably 85 made of flat spring metal, to effect a tight grip or normal pinching engagement with the hair in the undivergent portion, so as to firmly hold the same.

The shoulders 10 at the end bars 8 and 9 serve as stops for the ring 11, but those on the end bar 9 also prevent the jaws 12 from moving out of alignment in the said 95 vertical plane.

Thus, the three-point contact of the indented end, guides the jaws freely into and out of position between the bars. At the opposite end, I prefer to join the wire ends by spot-welding in order to present a continuous union of metal.

In using the device, the hair 13 to be curled is first introduced between the open jaws as shown in Fig. 3, and when the hair has been thus arranged as shown in Fig. 4 105 and properly gripped by the jaws the necessary turning action may be imparted to the jaws to wind the hair thereon. The jaws in this particular case (Fig. 4) may be turned in either direction to obtain the desired kind 110 of curl.

In Fig. 5, the jaws have been turned in-

wardly toward the head, to wind, so to speak, the hair upon it to produce a curl at the hair ends as shown in Fig. 6; whereas in Fig. 7, the hair 14 has first been pinched as in Fig. 4, then given an inward turn, then twisted or roped, and finally wrapped around the jaws. This manipulation will simultaneously produce a Marcel wave in the body of the hair, and a curl at the end of the hair 10 as shown in Fig. 9.

So far as the manner of use is concerned, my device does not materially distinguish from well known devices of the kind, but the particular combination of the frame, jaws 15 and locking ring, enables me to accomplish results that these other devices can not possibly realize. I have found in practice that by making the locking ring free to slide substantially the entire length of the side bars, 20 that I can jam the ring tightly against the engaged hair and positively lock the hair on and in the jaws, and also securely lock the jaws in the frame. This is a desirable feature not found in other curlers of this type, 25 consequently they employ other means to grip or lock the end only of the winding member. In such curlers, hair can not be securely gripped, especially when thin strands of hair are to be engaged and curled, and the extreme ends of the hair can not be gripped at all. Then again, the winding member of other curlers often pops out of the frame, because it is made of spring metal and where only the end of it was engaged, it 30 was an uncertain engagement with the hair. In my device, the sliding ring not only, as above stated, firmly anchors the hair ends between the jaws, but the said jaws, by reason of their divergence, tend to force the 35 ring toward the engaged hair for positive binding.

From the foregoing description taken in connection with the accompanying drawings, the advantages of the construction and 40 method of operation will be readily understood by those skilled in the art to which the invention appertains, and while I have described the principle of operation, together with the device which I now consider to be 45 the best embodiment thereof, I desire to have 50

it understood that the device shown is merely illustrative and that such changes may be made, when desired, as fall within the scope of the appended claims.

Having thus described my invention, what 55 I claim as new and desire to secure by Letters Patent of the United States, is the following:

1. A hair curler of the class described, comprising a frame having parallel side 60 bars spaced apart and end bars therefor, a pair of jaws consisting of a single piece of metal pivoted to one of the end bars, and a locking device slidably mounted on the frame and adapted to lock the jaws to the 65 side bars at any point along said jaws.

2. A hair curler comprising, a frame formed of a single piece of wire bent to provide spaced-apart parallel side bars and end 70 bars, a pair of jaws pivoted to one of the end bars, and a locking device mounted on the side bars adapted to slide over the jaws for substantially the length thereof, for locking the jaws within the frame.

3. A hair curler comprising an open rectangular frame, a pair of integral jaws pivotally mounted thereon for engagement within the frame, and a single-loop locking ring carried by the frame and adapted to slide over the frame and over the jaws for 80 substantially the length thereof.

4. A hair curler comprising, a frame formed of a single piece of wire bent to provide spaced parallel side bars and end bars 85 therefor, a pair of divergent flat spring jaws pivoted to one of the end bars, and a ring slidably carried by the frame adapted to slide over the jaws for substantially the length thereof.

5. A hair curler comprising, a frame 90 formed of a single piece of wire bent to provide spaced parallel side bars and end bars therefor, a pair of jaws pivoted to one of the end bars, a ring slidably carried by the frame adapted to slide over the jaws for substantially the length thereof, and shoulders 95 on the end bars for confining the ring on the frame.

In testimony whereof I affix my signature.

GERTRUDE G. CONDON.
